Jeremy I. Maynard**CLAIM**

The ornamental design for the incontinence pouch, as shown and described.

DESCRIPTION

FIG. 1 is a front view of an incontinence pouch;
FIG. 2 is a rear view of the incontinence pouch;
FIG. 3 is a right-side view of the incontinence pouch;
FIG. 4 is a left-side view of the incontinence pouch;
FIG. 5 is a top view of the incontinence pouch;
FIG. 6 is a bottom view of the incontinence pouch;
FIG. 7 is a left-side perspective view of the incontinence pouch; and,
FIG. 8 is a right-side perspective of the incontinence pouch.
The shading of FIG. 2, FIG. 7, and FIG. 8 indicates layers,
rather than connected, continuous surfaces.

1 Claim, 8 Drawing Sheets(56)
